BEER COOLER DEVICE

John Panagopoulos, Youngstown, Ohio

Application January 26, 1937, Serial No. 122,378

5 Claims. (Cl. 225—40)

This invention relates to beer coolers.

The principal object of this invention is to provide a device of this class which is utilized for the purpose of cooling keg or barrel beer when placed on tap.

A further object is to provide a device that is simple and direct in operation, and compact and efficient in its cooling of beer on tap.

A further object is to provide a cooling unit which is suspended in the barrel from its head and which may be easily removed from the barrel when desired.

A further object is to provide means for easily detaching the suspended cooling unit from the barrel.

A further object is to provide means for efficiently sealing the cooling unit support when installed in a barrel.

A further object is to provide a plurality of screened beer intakes when the beer is being drawn from the barrel.

A still further object is to provide a beer cooling unit suspended within a barrel and comprising an upper circular tubular member and a lower circular tubular member wherein each circular tubular member is joined by a plurality of vertical tubes.

With the foregoing and other objects in view which will appear as the description proceeds, the invention resides in the combination and arrangement of parts and in the details of construction hereinafter described and claimed, it being understood that changes in the precise embodiment of the invention herein disclosed, can be made within the scope of what is claimed, without departing from the spirit of the invention.

The invention is illustrated in the accompanying drawing, wherein:—

Figure 1 shows a vertical view of the device installed in a barrel with the cooling tank underneath a bar in cross section.

Figure 2 is an enlarged view of the barrel and parts therein in cross section.

Figure 3 shows a slight modification of the barrel and the manner of installing the suspended beer cooling unit within the barrel.

Figure 4 is an enlarged detailed view of a unit partly in cross section, showing the means of installing and sealing a support for the beer cooling unit suspended within the barrel.

Figure 5 is a cross section taken on line A—A, Figure 2.

Figure 6 is an enlarged detailed view partly in cross section showing a screened beer intake at a central position at the bottom of the barrel.

By referring to Figure 1 of the drawing it will be seen that there is provided a cooling tank 1 suspended underneath a dispensing bar 2, this bar 2 showing a trough 3 on its inner edge and directly beneath that a tap 4 for the purpose of drawing beer or any other fluid desired to be cooled. It will also be seen that the tap 4 is attached to a tube 5 which runs inwardly and downwardly through the cooling tank 1 and down through a downwardly extended cooling jacket 6. The tube 5 is connected at a point 7 by a coupling 8 to a beer outflow tube 9 upwardly extended from barrel 10.

By referring to Figures 2 and 4 it will be seen that the barrel 10 is provided with a head 11 having a central circular opening into which is fitted a circular ring member 12 provided with an upper outwardly extended flange 13 and a lower inwardly extended seat member 14. Upon this seat member 14 there is provided a circular gasket 15. Upon this circular gasket 15 there is provided a circular plate support member 16 thus installing the unit within the barrel. The cooling unit within the barrel is supported by this circular plate support member 16 by having attached thereto a tubular cooling passage-way 17 and a second tubular cooling passage-way 18. It will also be seen by referring to Figure 2 that the beer outflow tube 9 is projected upwardly through a central opening of the circular plate support member 16. The tubular cooling passage-way 17 connects to an upper tubular ring 19 which has a plurality of vertical tubes 20 attached thereto and having their lower ends attached to a tubular ring 21. It will be seen that the tubular ring 19 and the lower tubular ring 21 are spaced apart by the plurality of vertical tubes 20 and are parallel to each other. It will be seen that the lower tubular ring 21 is provided with the tubular channel 22 connecting to a vertical circular jacket 23 which has enclosed a beer outflow tube 9.

In installing the circular plate support member 16 it is first placed upon the circular gasket 15 and then a pressure ring 24 provided with exterior threads is turned down into the central opening of the circular ring member 12 functioning with the threads 25 formed on the inner surface of the circular ring member 12. In order to turn the pressure ring 24 down firmly upon the circular plate support member 16 there is provided a pair of oppositely disposed circular recesses formed on the upper surface of the pressure ring 24, one of which is shown at a point 26. It is understood that any suitable tool may be used in connection with the oppositely disposed

circular recesses in order to turn down or remove the pressure ring 24.

By referring to Figures 2 and 6 it will be seen that the lower end 27 of the beer outflow tube 9 is provided with a cap 28 having a plurality of horizontal inlets 29 leading to a screen member 30 guarding lower end 27 of the beer outflow tube 9.

By referring to Figures 1 and 2 it will be seen that there is provided a circulating means for the suspended cooling unit within the barrel comprising a pressure tube 31 leading to the cooling tank 1 at a point 32. It will be understood that any suitable pump may be placed so as to join an end 33 of the pressure tube 31 and an end 34 of the second tubular passage-way 18.

By referring to Figure 3 it will be seen that there is provided a steel barrel 35 showing the suspended cooling unit positioned in the head 36 of the steel barrel 35. It will be seen that a receiving ring 37 is welded at a point 38 and that the circular plate support member 16 is held in position similarly as shown in Figure 4 where the installation is in a wooden head.

25 What I claim is:—

1. In a device of the class described, a barrel, a circular suspension plate positioned in a head of said barrel, a cooling unit suspended on the underside of said circular suspension plate, means for securing and removing said suspension plate, a cooling tank positioned above said barrel, tubes connecting said cooling tank and cooling unit in order to provide circulating means between the cooling tank and suspended cooling unit, an outlet tube centrally positioned in said cooling unit, a screened lower end of said outlet tube and positioned centrally at the bottom of said barrel.

2. In a device of the class described, a barrel, a circular suspension plate positioned in a head of said barrel, a cooling unit suspended on the underside of said circular suspension plate, means for securing and removing said suspension plate comprising a circular ring member positioned in the head of the barrel, a circular gasket carried by the circular ring member and the circular suspension plate positioned on the upper surface of said gasket, a threaded circular pressure ring functioning with a threaded interior of said circular ring member, a cooling tank positioned above said barrel, tubes connecting said cooling tank and cooling unit in order to provide circulating means between the cooling tank and suspended cooling unit, an outlet tube centrally positioned in said cooling unit, a screened lower end of said outlet tube and positioned centrally at the bottom of said barrel.

3. In a device of the class described, a barrel, a circular suspension plate positioned in a head of said barrel, a cooling unit comprising a pair of tubular rings spaced apart by a plurality of vertical tubes together with a centrally positioned

jacket connected to the lower one of said tubular rings, the said cooling unit being suspended on the underside of the said circular suspension plate, means for securing and removing said suspension plate comprising a circular ring member positioned in the head of the barrel, a circular gasket carried by the circular ring member and the circular suspension plate positioned on the upper surface of said gasket, a threaded circular pressure ring functioning with a threaded interior of said circular ring member, a cooling tank positioned above said barrel, tubes connecting said cooling tank and cooling unit in order to provide circulating means between the cooling tank and suspended cooling unit, an outlet tube centrally positioned in said cooling unit, a screened lower end of said outlet tube and positioned centrally at the bottom of said barrel.

4. In a device of the class described, a metal barrel, a circular suspension plate positioned in a head of said barrel, supporting means for said circular suspension plate comprising a welding to said barrel head of said supporting means, a cooling unit suspended on the underside of said circular suspension plate, means for securing and removing said suspension plate, a cooling tank positioned above said barrel, tubes connecting said cooling tank and cooling unit in order to provide circulating means between the cooling tank and suspended cooling unit, an outlet tube centrally positioned in said cooling unit, a screened lower end of said outlet tube and positioned centrally at the bottom of said barrel.

5. In a device of the class described, a barrel, a circular suspension plate positioned in a head of said barrel, a cooling unit comprising an upper and lower tubular ring spaced apart by a plurality of vertical tubes together with a centrally positioned jacket spaced apart from outlet tube having a tube connecting the lower tubular ring and the jacket and suspended on the underside of said circular suspension plate, means for securing and removing said suspension plate comprising a circular ring member positioned in the head of the barrel, a circular gasket carried by the circular ring member and the circular suspension plate positioned on the upper surface of said gasket, a threaded circular pressure ring functioning with a threaded interior of said circular ring member, a cooling tank positioned above said barrel, tubes and a downwardly extending cooling jacket formed at the bottom of said cooling tank thereby connecting said cooling tank and cooling unit in order to provide circulating means between the cooling tank and suspended cooling unit, an outlet tube centrally positioned in said cooling unit, a screened lower end of said outlet tube and positioned centrally at the bottom of said barrel.

JOHN PANAGOPOULOS.
